UNITED STATES PATENT OFFICE.

PATRICK HAGENEY, OF ASHTABULA HARBOR, OHIO.

METALLIC RAILWAY-TIE.

968,049.

Specification of Letters Patent. Patented Aug. 23, 1910.

Application filed August 18, 1909. Serial No. 513,873.

To all whom it may concern:

Be it known that I, PATRICK HAGENEY, a citizen of the United States, residing at Ashtabula Harbor, in the county of Ashtabula and State of Ohio, have invented a certain new and useful Improvement in Metallic Railway-Ties, of which the following is a full, clear, and exact description.

The object of this invention is to provide a metallic railway tie adapted to support and to be easily connected with the rails without the use of bolts, and which, when once laid, is not liable to shift its position.

The invention consists in the construction and combination of parts hereinafter described and pointed out definitely in the claims.

In the drawing, Figure 1 is a plan view of a railway tie. Fig. 2 is a bottom plan view thereof. Fig. 3 is a side elevation thereof and Fig. 4 is a sectional view in the plane indicated by the line 4—4 on Fig. 1.

The tie is composed of two duplicate members A, A. Each member consists of a plate 25 having end portions a which serve as rail seats; a middle portion a' located in a plane below said seats; and inclined portions a^2 which are intermediate of the middle portion and rail seats. Along one edge of the 30 portions a' and a^2 is an upwardly extended vertical flange a^3 in which is a horizontal slot a^4 . A flange a^5 also extends downward from the same edge of each member, said flange extending from one end of the member to the other. A hook a^6 is formed upon or secured to this flange at one end thereof.

Each tie has two rail engaging fingers a^7 , a^8 ,—one formed upon each rail seat. Each tie member has also a perforated bracket a^9 40 rising through the middle portion a' . Two of these members, which are identical in shape and construction, are placed with their flanged edges in contact. A flat bar B goes through the two slots a^4 . The ends of this 45 bar are threaded and go through the holes in the two brackets a^9 . By turning nuts C onto the ends of this bar, the two tie members are moved relatively endwise.

The two rails D have in the meantime 50 been placed on the rail seats, the flanges d of the rails being placed between the two opposed fingers a^7 , a^8 , of the respective members the relative endwise movement of the two tie members draws these fingers of each pair toward each other and into overhanging engagement with said rail flanges. The

same relative endwise movement of the tie members cause each of the hooks a^6 on the two tie members respectively to engage the adjacent end of the flange a^5 on the other member, and thereby the two tie members are held against separation by relative lateral movement. The bar B not only holds the tie members against relative endwise movement, but also holds them against relative vertical movement because said bar fits the slots a^4 . Strengthening ribs a^{10} may be formed on the under side of the rail seats.

When these ties have been laid, and the two members moved so as to grasp the rails, 70 as stated, and when the earth has been tamped beneath them there is very little likelihood that they will shift their position. The broad flat under surfaces practically prevent settling down. The flanges 75 a^5 being buried in the earth resist any tendency to move the ties in the direction parallel with the rails. The inclined parts a^2 resist any tendency of the ties to move crosswise of the rails.

Having described my invention, I claim:

1. A railway tie comprising two members, each of which has a horizontal plate upon which is a rail seat near each of its ends, a slotted vertical flange extending above said plate and between said rail seats, and a bracket, combined with a connecting bar which goes obliquely through said slotted flanges and brackets, and nuts which screw on to the ends of said bar to draw the members relatively endwise and hold them in operative position.

2. A railway tie comprising two members, each of which has a horizontal plate upon which is a rail seat near each of its ends, a slotted vertical flange extending above said plate between said rail seats, and a bracket, combined with a connecting bar which goes obliquely through and is fitted in the slots in said flanges and which at its ends goes through said brackets, and nuts which screw on to the ends of said bar to draw the members relatively endwise and hold them in operative position.

3. A railway tie comprising two members, 105 each of which has a horizontal plate upon which is a rail seat near each of its ends, a slotted vertical flange extending above said plate between said rail seats, a bracket, a hook at one end and a depending flange at 110 the other end, combined with a connecting bar which goes obliquely through said slot-

ted flanges and brackets, and nuts which screw on to the ends of said bar to draw the members relatively endwise and hold them in operative position.

- 5 4. A railway tie comprising two members, each of which has a broad plate, the ends of which serve as rail seats, a middle portion located in the plane below said rail seats, and inclined portions extending between and 10 connected with the middle portion and said rail seats, an upwardly projecting flange along one edge of the middle portion and the inclined portions of said plate, said flange being horizontally slotted, and a bracket rising 15 from the middle portion of said plate, combined with a connecting bar which goes obliquely through said slotted flanges and brackets, and nuts which screw on to the ends of said bar.
- 20 5. A railway tie comprising two members, each of which consists of a broad plate having end portions which are in the same horizontal plane and serve as rail seats, a middle portion in a horizontal plane below that 25 of the rail seats, and inclined intermediate portions extending between and connecting said middle portion and rail seats, a downwardly extended flange along one edge of each plate extending from end to end, an 30 upwardly extended flange rising from the corresponding edge of the middle and inclined portions of said plate, said flange being horizontally slotted, and a bracket rising 35 from the middle part of said plate, combined with a connecting bar which goes obliquely through the said slotted flanges and through said brackets, and nuts screwing 40 on to the ends of said bar.
6. In a railway tie, the combination of two identical longitudinal members each having a horizontal plate portion with a rail seat near each of its ends, and fingers on 45 the same sides of the rail seats overhanging

the vertical face of the side and pointing in the same longitudinal direction, vertical ribs or flanges on the meeting edges of the members, and a bolt provided with clamping nuts adapted to so engage both of said members as to draw them relatively endwise into operative relations bringing their opposed overhanging pairs of fingers into transverse clamping contact with their respective opposite sides of and directly across the base flanges of the rails, said bolt holding the members in such positions of engagement. 55

7. In a railway tie, the combination of two identical longitudinal members each having a horizontal plate portion with a rail seat near each of its ends, and integral fingers on the same sides of the rail seats overhanging the vertical face of the side and pointing in the same longitudinal direction, vertical ribs or flanges on the meeting edges of the members, a hook on one end of each member adapted to embrace the rib or flange of the other member and pointing in the same direction as said fingers of the member, a bolt provided with clamping nuts adapted to so engage both of said members as to draw them relatively endwise into operative relation, bringing the end hook of each member into locking engagement with the rib or flange of the other member and the opposed pairs of overhanging fingers into direct transverse clamping contact with their respective opposite sides of the base flanges of the rails, said bolt holding the members in such positions of engagement. 60

In testimony whereof, I hereunto affix my signature in the presence of two witnesses.

PATRICK HAGENEY.
